URINAL

Gerard D. Phillips, Jr., Louisville, Ky., assignor to American Radiator & Standard Sanitary Corporation, New York, N.Y., a corporation of Delaware

Filed Jan. 23, 1961, Ser. No. 63,641

Term of patent 14 years

(Cl. D4—5)

FIGURE 1 is a view in front elevation of a urinal showing my new design;

FIGURE 2 is a view in side elevation thereof;

FIGURE 3 is a top plan view; and

FIGURE 4 is a view in perspective.

The side not shown is substantially the same as that of FIGS. 2 and 4 and the back of the urinal is substantially plain.

The dominant features of my design reside in the portions thereof shown in full lines.

I claim:

The new and ornamental design for a urinal, substantially as shown and described.
